POWER-OPERATED WHEELBARROW

Herchael Wood Miller, Davenport, and Richard E. Andrews, Muscatine, Iowa, assignors to The Prime Mover Co., Muscatine, Iowa, a corporation of Iowa

Application January 13, 1951, Serial No. 13,786

Term of patent 7 years

(Cl. D14—3)

To all whom it may concern:

Be it known that we, Herchael Wood Miller and Richard E. Andrews, both citizens of the United States of America, residing, respectively, at Davenport, in the county of Scott, and State of Iowa, and at Muscatine, in the county of Muscatine, and State of Iowa, have invented a new, original, and ornamental Design for a Power-Operated Wheelbarrow, of which the following is a specification, reference being made to the accompanying drawings, forming a part thereof.

Fig. 1 is a rear perspective view of a power-operated wheelbarrow, showing our new design;

Fig. 2 is a front perspective view thereof; and

Fig. 3 is a corresponding view of Fig. 2, showing the same in dumping position.

The opposite side from that shown in the drawing is essentially a duplicate of that which is shown.

We claim:

The ornamental design for a power-operated wheelbarrow, substantially as shown and described.

HERCHAEEL WOOD MILLER.
RICHARD E. ANDREWS.
